INDIVIDUAL WARP TENSION DEVICE

George Holden, Philadelphia, Pa.

Application June 21, 1941, Serial No. 399,051

5 Claims. (Cl. 242—151)

My invention relates to a new and useful individual warp tension device and has for one of its objects to generally improve and simplify devices of this character for use in connection with looms of several types.

Another object of the invention is to provide a warp tension device that will maintain an even tension at all times thereby producing a more uniform product.

Another object of the invention is to provide a warp tension device so constructed and arranged that the warps can be tied on while the loom is in operation, thus resulting in a considerable saving of time and an increase in production.

Another object of this invention is to provide a warp tension device that will decrease waste because the weaver has to weave the work until the lease string appears.

Another object of the invention is to provide a warp tension device that causes the warps to run in vertical instead of horizontal directions, thereby decreasing the usual hazards to persons operating and attending to the looms.

A further object of the invention is to provide a warp tension device that can be readily and easily replaced with less experienced help.

A still further object of this invention is to provide the warp tension device with an adjustable sectional leg which can be swung in and out for disposition in an out of the way location and to a position of easy access, and said leg functions as a counter-balance for other parts.

With the above and other objects in view, this invention consists of the details of construction and combination of elements herein-after set forth and then designated by the claims.

In order that those skilled in the art to which this invention appertains may understand how to make and use the same, I will describe an embodiment in detail, referring by numerals to the accompanying drawing forming a part hereof, in which:

Fig. 1 is a side elevation of the warp tension device showing it mounted on a loom represented by one of the standards thereof.

Fig. 2 is a fragmentary sectional view to illustrate details of construction.

Fig. 3 is a side elevation of the box of the tension device illustrating the manner in which the tension is released.

Fig. 4 is a plan view of complete warp tension device.

Fig. 5 is a diagrammatic view of the several rollers in perspective to illustrate their relation to one another.

In carrying out my invention as herein embodied 10 represents the standards of a loom having bearing recesses 11 which are closed at

one side by the sliding closure plates 12 held in place by screws 13.

In the bearing recesses 11 are mounted the trunnions 14 of the axle 15 having a rearwardly projecting rigid leg section 16 to which is pivoted the swinging leg section 17. The outer free end of said leg section 17 is enlarged and has a chamber 18 in its top face providing a circular track 19 on which a turntable 20 or a spool 21 rests with the spindle 22, carried by the swinging leg section, as the axis.

Where the turntable is used, the spool 21 rests thereon and the top surface of said turntable is covered with a layer 23 of suitable material, such as felt, to reduce the likelihood of slippage of the spool relative to the turntable. Said turntable is normally urged in a direction that will wind the warp 24 on the spool by a coil spring 25 positioned in the chamber 18 with one end anchored to the swinging leg section and the other end fixed to the turntable.

A finger 26 also projects rearwardly from the axle 15 in the inward path of travel of the swinging leg section 17 and is frictionally engaged thereby to temporarily retain said swinging leg section in its folded position. The weight of the leg, including both of its sections, to some extent, counterbalances the box and component parts to be described below, but to prevent undue oscillation of the tension device, the rigid leg section 16 has an elongated hole 27 therein through which a screw 28 is projected and screwed into one of the standards 10.

The axle 15 also has a forwardly projecting arm 29, on the outer end of which is a bracket 30 carrying the box 31. This box has a bottom 32, a front wall 33, a back wall 34 and side walls 35. The front and back walls each have a vertical slot 36 of a size to accommodate the particular warp used on the loom equipped with the tension devices and these slots are open at their upper ends.

In each of the side walls 35 is an inverted Y-shaped slot 37 and preferably the stem, which is open at the upper edge of its respective side wall, is wider than the branches. The ends of the axles 38 of the idler rollers 39 rest in the lower parts of the branches of the slots 37, being inserted through the stems of said slots. A tension roll 40 is provided with journals 41, which are slightly smaller than the width of the stems of the slots 37 and rest therein, and also carry, what I term, brake drums 42. The circumference of the tension roll 40 is covered with a jacket 43 of textile or other suitable material to provide traction for or prevent slipping of the warp.

A pair of levers 44, preferably of the bellcrank type, are pivoted on the sides of the box 31, one on each side and preferably spaced from the box

a distance approximately equal to the width of the brake drums 42. The corresponding arms of the levers have cross bars 45 connected thereto so that the parts of the lever mechanism operate in unison.

Brake bands or drags 46 of flat spring steel embrace the brake drums 42 and one end of each band is anchored at the pivot point of its respective lever 44 and the other end of each of said bands is attached to one of the cross bars 45 through the medium of adjustment devices 51. These may include screweyes 52 mounted on the bar 45 and passing through connectors 53 on the brake bands and having nuts 54 screwed thereon. This arrangement allows independent adjustment of the brake bands whereby they may grip the brake drums evenly. The bands have linings 47 to contact the brake drums. The lever mechanism is resiliently urged in a direction that will apply the brake bands to the brake drums by means of coil springs 48 having one end of each anchored on the box 31 and the other end of each connected to a screw 49 projected through the other cross bar 45 with a butterfly or equivalent nut 50 threaded on each screw and bearing against the cross bar for regulating the tension of each spring 48.

To thread the tension device the lever mechanism is released, the brake bands slipped from the brake drums and the tension roll and idler rollers lifted out. The warp 24 is then placed in the slots 36 and the idler rollers replaced. Next, the warp between the idler rollers is pulled up to form an open loop or sling and the tension roll is inserted therein and said tension roll replaced. Finally the brake bands are repositioned and the tension adjusted.

When the tension device is threaded and ready for use, the warp runs under the cross bar to which the brake bands are connected and then upward as illustrated in Figs. 2 and 3 so that any pull on the warp has a tendency to lift this cross bar against the action of the springs 48 thereby releasing the brake bands, more or less, from the brake drums to relieve the pressure of the tension roll on the warp in proportion to the pull on the warp. As a knot in the warp passes between the first idler roller and the tension roll, the latter will be moved to one side to permit the knot to pass and when such knot reaches the next idler roller the tension roll will be moved in the opposite direction to open a space between said next idler roller and the tension roll to permit the knot to pass them without binding.

The limited oscillating movements of the tension device as a whole, as controlled by the stop screw 28, will temporarily relieve any snapping pull or back lash on the warp resulting in a more even progressive tension on the warp even though knots or imperfections occur which might cause a fluttering action in the warp.

As the warp is withdrawn from the spool the turntable 20 will be rotated a limited distance, or until the spring 25 becomes wound up, then when the warp is released from the tension device said turntable will be rotated in the opposite direction by the spring thereby rewinding a portion of the warp on the spool to take up the slack.

When additional warp is to be tied on the swinging leg section 17 can be swung out for easy access thereto and then moved back to place so there will not be too great a counter action on

the box and its component parts and the leg with the spool thereon will be out of the way of persons passing along in back of the loom or between banks of looms.

5 Of course I do not wish to be limited to the exact details of construction herein shown and described, as these may be varied within the scope of the appended claims without departing from the spirit of my invention.

Having described my invention, what I claim as new and useful is:

1. An individual warp tension device comprising an axle to be journaled in standards of a loom, an arm projecting from said axle, a box supported by said arm, idler rollers mounted in said box, a tension roll also mounted in the box and lying above and between said idler rollers and coacting therewith, brake drums carried by the tension roll, mechanism including brake bands engaging the brake drums and operable by the warp to relieve the action of the brake bands on the brake drums, and means to hold a spool.

2. A warp tension device comprising an axle, an arm projecting therefrom, a bracket at the outer end of said arm, a box supported on the bracket and including a bottom and vertically slotted front and back walls and side walls having inverted Y-shaped slots formed therein, idler rollers, axles therefor having their ends loosely engaged in the branches of the Y-shaped slots for removably mounting said idler rollers within the box, a tension roll, trunnions on the tension roll loosely fitting the stems of the Y-shaped slots to permit angular movements of the tension roll relative to the idler rollers with which said tension roll cooperates, brake drums on the trunnions and located outside of the box, bell crank levers mounted on opposite sides of the box, cross bars fixed to the ends of corresponding legs of said bell crank levers, brake bands at opposite sides of the box and engaging the brake drums, one end of each of said brake bands being anchored on the box and the other end of each being connected to one of the cross bars, longitudinally adjustable screws connected with the other cross-bar, and springs each having one end connected to one of the adjustable screws and the other end anchored on the box.

3. The structure in claim 2 in combination with a jacket of textile material covering the tension roll.

4. The structure in claim 2 wherein the brake bands are produced from flat spring metal and have friction linings in the region thereof engaging the brake drums.

5. An individual warp tension device comprising an axle to be journaled in standards of a loom, an arm projecting from said axle, a box supported by said arm, idler rollers mounted in said box, a tension roll also mounted in said box and lying above and between said idler rollers and coacting therewith, brake drums carried by said tension roll, bell crank levers pivoted intermediate their ends to the outside of the box, bars connected to the corresponding ends of both levers, one of said bars to be engaged by warp from the loom, tensioning means connected to the box and the other bar, brake bands anchored at the pivot points of the levers and engaging the brake drums, and an adjustment device to adjustably connect each brake band with the bar to be engaged by the warp.

GEORGE HOLDEN.
